United States Patent Office.

WILLIAM McFARLAND, OF WILLIAMSBURG, NEW YORK.

Letters Patent No. 100,781, dated March 15, 1870.

IMPROVEMENT IN BURGLAR-PROOF SAFES.

The Schedule referred to in these Letters Patent and making part of the same.

To all whom it may concern:

Be it known that I, WILLIAM McFARLAND, of Williamsburg, in the county of Kings, and State of New York, have invented a new and useful Improvement in Burglar-Proof Safes; and I do hereby declare that the following is a full, clear, and exact description thereof, which will enable others skilled in the art to make and use the same, reference being had to the accompanying drawings forming part of this specification.

Figure 1 is a detail cross-section of the joint between the door and body of the safe.

Figure 2 is a detail sectional view of the safe-door taken through the line α , fig. 1, looking in the direction of the arrow, and parts being broken away to show the construction.

Similar letters of reference indicate corresponding parts.

My invention has for its object to improve the construction of burglar-proof safes in such a way that it will be impossible to blow powder through the joint between the door and body of the safe to blow the door open; and

It consists in an open spring ring inserted in a flange or shoulder of the door and body, either or both within the steel and iron-ribbed plates in such a way as to bear against a flange or shoulder of the other part, as hereinafter more fully described.

A represents the body of the safe, of which a^1 is the outer heavy iron band, and a^2 is the ribbed plate of iron and steel.

B is the door of the safe, of which b^1 is the outer heavy iron plate, and b^2 is the ribbed iron and steel plate. The joint between the door B and body A of the safe is formed of a series of inclined flanges or shoulders, as shown in fig. 1.

b^3 is a plate of the door within the iron and steel-ribbed plate b^2 . The edge of the plate b^3 is grooved or channeled, as shown in figs. 1 and 2.

In this groove or channel is placed the bars C that form the open or powder-ring.

The parts of the open ring C are secured in place by screws D which pass through holes in the said bars and screw into the solid body of the plate b^2 .

The holes in the bars C through which the screws D pass, are deeply countersunk at their outer ends, so that the said bars may be pushed inward without causing the heads of the screws D to project beyond the outer surface of the said bars.

E are coiled or equivalent springs placed between the bars C and the body of the plate b^2 to hold the bars C that form the powder-ring pressed outward.

The short curved bar that passes around the rounded corners of the safe, is made in three parts hinged to each other, as shown in fig. 2. The ends of the

hinged parts of the curved corner bar, and the adjacent ends of the straight bars, are beveled with a curved or straight bevel, so that the said ends may overlap and slide upon each other as the open ring moves in and out. The screw D that secures the curved corner bars to the plate b^2 enters the said plate diagonally, as shown in fig. 2.

The necessity of making the curved corner-bars jointed arises from the fact, that, as the door swings shut, the top and bottom bars C of the powder-ring begin to be pressed in at their ends next the hinged edge of the door, so that the ends of the corner or curved bars are pressed in before the middle parts of said curved bars are acted upon.

The hinged ends of the curved corner-bars are held out against the overlapping adjacent ends of the straight bars by a spring, F, connected with the inner side of the said corner-bars, as shown in fig. 2. The outer side or face of the open ring C is beveled or rounded off, as shown in fig. 1. By this construction, when the door is swung shut the beveled face of the bars C strikes against the flange or shoulder of the body of the safe, and the said ring is forced inward.

The rounded or beveled faces of the bars C, and the action of the springs F acting together, roll the said bars slightly, so as to force their outer edges against the inner side of the steel plate b^2 at the same time that their faces are pressed against the flanges of the body of the safe, thus closing the joint so closely that it will be impossible to blow powder in through the said joint.

The open spring-ring C may be placed in the door or in the body of the safe, or in both, but in all cases the ring or rings must be placed within the steel and iron-ribbed plates, so that it will be impossible for the said ring or ring-chamber to be reached by drilling.

Having thus described my invention, I claim as new, and desire to secure by Letters Patent—

1. The open spring-ring C inserted in a groove or channel in the door or body, either or both, of the safe, and pressing against the other of said parts, substantially as herein shown and described and for the purpose set forth.

2. The hinged curved corner-bars or pieces C, constructed and operating in connection with the straight bars of said ring C and with the rounded corners of the body and door of the safe, substantially as herein shown and described and for the purpose set forth.

The above specification of my invention signed by me this 27th day of January, 1870.

WM. McFARLAND.
